ELEVATOR CAB

Delmar S. Mitchell, San Diego, Calif.

Application June 7, 1956, Serial No. 41,802

Term of patent 14 years

(Cl. D41—1)

FIG. 1

I claim:

The ornamental design for an elevator cab, substantially as shown.
